UNITED STATES PATENT OFFICE.

PHILIP H. LECKINGER, OF ROCHESTER, NEW YORK.

ADJUSTABLE SUPPORT FOR CHAIR-BACKS.

SPECIFICATION forming part of Letters Patent No. 740,290, dated September 29, 1903.

Application filed April 25, 1902. Serial No. 104,651. (No model.)

To all whom it may concern:

Be it known that I, PHILIP H. LECKINGER, a citizen of the United States, residing at Rochester, New York, have invented certain improvements in Adjustable Supports for Chair-Backs, of which the following is a specification, reference being had to the accompanying drawings.

My invention relates to improved adjustable supports for chair-backs, which improvements are fully described and illustrated in the following specification and the accompanying drawings, the novel features thereof being specified in the claims annexed to the said specification.

In the accompanying drawings, Figure 1 is a side elevation. Fig. 2 is a side view of the support. Fig. 3 represents a modification. Fig. 4 is a plan view of the support, partially in section. Fig. 5 represents the clip by which the link is pivoted to the back. Fig. 6 represents the movable catch detached. Fig. 7 is a section on the line 7-7, Fig. 4. Fig. 8 represents the movable catch.

My improvement is applicable to any style of chair having a swinging or pivoted back.

In the accompanying drawings, 11 represents the back, which is ordinarily arranged to be lowered to the position indicated by the dotted lines 12, Fig. 1. A clip 10 is attached to the back and receives the bent end of the link 9. The front end of the link is attached by a suitable joint, such as a hook and eye 8, to the rear end of a sliding rod 7, arranged to move lengthwise of a suitable support 19, which may be cylindrical, as shown in Figs. 2 and 4, or a bar, as shown in Fig. 3. The cylindrical support is attached to the body of the chair by the sockets 2 and the lugs 1. A slot 3 is made in the support, and this slot is provided with the notches 4 along one of its edges or the perforations 4, Fig. 4, arranged opposite the slot. On the rod is attached a boss or head 16, and a spring 15 is arranged on the rod bearing at one end against the support, and at the other against the boss or against a washer 17, interposed between the spring and boss. The nut 18 can be used to hold the boss and washer against the thrust 50 of the spring.

14 is a pin or catch fixed on the head 16, rotatable on the rod, which may be provided

with any preferred handle or knob 5. The back is readily adjusted to any desired position by disengaging the catch from one of the notches, as represented at 6, Fig. 1, and engaging it in any of others. In order to make the catch engage automatically with the notches, the spring 15 is fastened at one end to the support and at the other to the boss 60 and is twisted, so that it will have a constant tendency to rotate the catch toward the notches. The ends of the spring are inserted in holes in the sockets 2 and the boss 16, as indicated in Fig. 3.

25, Fig. 3, is a pin which may be employed instead of the nut 18.

In Fig. 4 the catch 14 is made to slide across the support, its point 23 engaging in the notches 4 and a spring 21 being arranged to press it outward by acting on the collar 22. A curved washer 24 is attached to the catch 14, being arranged so that by giving the catch a quarter-turn on its axis its point will be held in out-of-engagement with the notches 4, in which case the back may be raised or lowered to any desired position, being then secured in place by another quarter-turn of the catch.

I claim—

1. The combination with the swinging back of a chair, of the clip attached to the back, the link pivotally connected to the clip, the sliding rod pivotally connected to the link, the pin fixed to a head rotatably connected to the rod, said head, the cylindrical support secured to the chair-body and provided with a slot having notches along one edge, and the spring secured to the cylindrical support and to the head to cause the engagement of the pin with either of the notches, as and for the purposes set forth.

2. The combination with the swinging back of a chair, of the clip attached to the back, the link pivotally connected to the clip, the sliding rod pivotally connected to the link, the pin fixed to a head rotatably connected to the rod, said head, the notched support secured to the chair-body, and the spring connected to the support and to the head and arranged to lift the back and to automatically engage the pin in any one of the notches, as and for the purposes set forth.

3. The combination with a frame and a mov-

- able back portion thereon, of a guide on the frame, a movable member in the guide attached to the back portion, of a locking member carried on the movable member and adapted to engage the guide and a spring yieldingly supporting the movable member in the guide and operating upon the locking member to cause its engagement with the guide.
- 10 4. The combination with a frame, a movable back portion thereon and a guide provided with a rack and attached to one of the parts, of a bar movable in the guide and attached to the other portion of the chair, a pawl on the bar and a spring engaging the pawl to throw it into engagement with the rack and operating to move the bar in one direction in the guide when the pawl is released.
- 15 5. An attachment for adjustable furniture, embodying a tubular guide having apertures

therein, a bar movable in the guide and a pawl carried on the bar adapted to engage said apertures and provided with an operating-handle, a spring attached to the guide and pawl to throw the latter into operative position and to move the bar in the guide when the pawl is released.

6. In a chair, the combination with a frame, a movable back portion thereon, a guide on the frame, a series of teeth on the guide, a longitudinally-movable and revoluble locking member in the guide, connections between said member and the back, and means for yieldingly supporting and revolving said locking member to engage the teeth on the guide.

PHILIP H. LECKINGER.
